US0D1096757S

(12) **United States Design Patent** (10) Patent No.: **US D1,096,757 S**
(45) Date of Patent: ** Oct. 7, 2025

(54) **DISPLAY FOR AN ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Eric Wesley Bates**, San Jose, CA (US); **Lucy E. Browning**, San Francisco, CA (US); **Mu-Hua Cheng**, Mountain View, CA (US); **Ihtesham H. Chowdhury**, Los Altos, CA (US); **Sawyer Isaac Cohen**, Menlo Park, CA (US); **Markus Diebel**, San Francisco, CA (US); **Richard Hung Minh Dinh**, Saratoga, CA (US); **M. Evans Hankey**, San Francisco, CA (US); **Julian Hoenig**, San Francisco, CA (US); **Richard P. Howarth**, San Francisco, CA (US); **David A. Hurrell**, San Mateo, CA (US); **Jonathan P. Ive**, San Francisco, CA (US); **Julian Jaede**, San Francisco, CA (US); **Hugh J. Jay**, Mountain View, CA (US); **Duncan Robert Kerr**, San Francisco, CA (US); **Matthew Rao**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/938,743**

(22) Filed: **Apr. 23, 2024**

Related U.S. Application Data

(63) Continuation of application No. 29/845,830, filed on Jul. 11, 2022, now Pat. No. Des. 1,025,075, which is a continuation of application No. 29/660,990, filed on Aug. 23, 2018, now Pat. No. Des. 957,400.
